[57] **CLAIM**

The ornamental design for the pager phone having belt loop, as shown and described.

DESCRIPTION

FIG. 1 is a perspective view of a pager phone having belt loop showing my new design;

FIG. 2 is a side elevational view thereof the opposite side being a mirror image;

FIG. 3 is a top plan view thereof;

FIG. 4 is a front elevational view thereof;

FIG. 5 is a rear elevational view thereof; and,

FIG. 6 is a bottom plan view thereof.

The broken line showing of a belt passing through the belt loop of the pager phone is for illustrative purposes only and forms no part of the claimed design.
